UNITED STATES PATENT OFFICE.

STEPHEN R. STINARD, OF CANANDAIGUA, NEW YORK.

IMPROVEMENT IN OMNIBUS AND CAR REGISTERS.

Specification forming part of Letters Patent No. 38,704, dated May 26, 1863; antedated March 13, 1863.

To all whom it may concern:

Be it known that I, STEPHEN R. STINARD, of Canandaigua, in the county of Ontario and State of New York, have invented a new and Improved Omnibus or Street-Car Register; and I do hereby declare that the following is a full, clear, and exact description of the same, reference being had to the accompanying drawings, forming a part of this specification, in which—

Figure 1 represents a front elevation of a street-car with my improved register. Fig. 2 is a side elevation of the same. Fig. 3 is a detached transverse section of the door and spring-step of a street-car, taken in the plane indicated by the line $x\ x$, Fig. 2. Fig. 4 is a similar view of the door and spring-step of an omnibus, the plane of section being indicated by the line $y\ y$, Fig. 1.

Similar letters of reference indicate corresponding parts in the several figures.

The object of this invention is to prevent the ingress and egress of passengers into street-cars or omnibuses against the will or without the knowledge of the driver, and at the same time to indicate the correct number of passengers which enter and leave the vehicle, thereby preventing frauds upon the proprietors of such vehicles.

The invention consists in the arrangement of a spring-bolt operated by means of a hand or foot lever and connected to the same by suitable rods and levers, in combination with the door of a street-car, omnibus, or other public conveyance intended to carry passengers, in such a manner that said door is firmly closed, and that it cannot be opened either from the inside or outside without the consent of the driver.

It consists also in the arrangement of a lip projecting from the under edge of the door and catching under a spring-step, the oscillating motions of which serve to impart motion to the registering mechanism in such a manner that said step is held perfectly firm as long as the door is closed, and no motion can be imparted to the registering mechanism before the door is opened to let a passenger in or out.

To enable those skilled in the art to make and use my invention, I will proceed to describe its construction and operation with ref-

erence to the drawings, and in order to render the whole more intelligible I will first describe the application of my invention to street-cars and afterward point out the changes requisite to render it available for omnibuses and other conveyances.

A represents the platform or driver's stand of a street-car, B, and one or more steps lead from this platform to the ground. The passage leading to these steps is closed by a door, C, and a bolt, b, which is secured to said door, serves to fasten or lock the same. This bolt catches behind a nose, e, that is inserted into the side of the car-body, and it is operated by an elbow-lever, d e, which is fulcrated on a vertical pivot, f, and one arm of which catches into a slot in the tail end of the bolt, whereas its other end connects by means of a rod, g, with a bell-crank lever, D E. The loose arm E of this lever extends through to the driver's stand, and it forms a foot-lever in convenient reach of the driver. A spring, h, which connects by means of a link, h', with the arm D of the lever D E, has a tendency to close the door as soon as the arm E is released.

In practice, the bolt and all the parts requisite to operate it will be concealed so that said bolt cannot be meddled with, and that the door can only be opened by depressing the arm E of the lever D E. If the door is to be operated from the driver's seat, the bolt b' connects by a curved arm, d', with a vertical arbor f', and an arm, e', on the upper end of said arbor, connects by a rod, g', with a hand-lever, D', that is in convenient reach from the driver's seat.

F is the spring-step which swings on trunnions or tenons h^x, and which, when the door is closed, rests with its front edge on the lip i, projecting from the inside surface of the door. The axle or one of the trunnions of said spring step connects by means of a rod, j, with the registering mechanism G, which is constructed of two or more ratchet-wheels and two pawls, both connected to an oscillating arm, to which the rod j is secured. One pawl propels the unit-wheel and the other pawl slides on the periphery of a disk which is firmly secured to the axle of the first ratchet-wheel, and rotates with the same. Said disk is provided with one notch, and whenever the sec-

ond pawl comes opposite to said notch it engages with one of the teeth of the second ratchet-wheel and propels the same one tooth. The second ratchet-wheel is secured on a hollow axle which fits on the solid axle, carrying the first ratchet-wheel and the notched disk, and each of these axles carries an index, one to indicate the units and the other the tens. Whenever the step F is depressed the first ratchet-wheel is propelled one tooth, and two teeth of this wheel indicate one passenger. The step will not operate the index while the door is fastened, and if a passenger desires to get in the driver opens the door, and as soon as the weight of the passenger comes to bear upon the step F the first index is propelled. As soon as the passenger has reached the platform the door is closed and the step is locked, so that if a passenger should accidentally step on it the registering mechanism is not affected. If a passenger wishes to go out the driver has to open the door, and if now the weight of the passenger bears on the spring step, the unit index is propelled, and each two motions, one on entering and one on going out, of each passenger count for one person. By these means a correct account is kept of the number of passengers, and the

driver has perfect control over the coming in and going out of passengers, so that all danger from jumping on or off while the vehicle is in motion is avoided, and each passenger will be correctly registered, no more and no less, it being impossible to impart motion to the spring-step or registering apparatus until the driver opens the door to let a passenger in or out.

Having thus fully described my invention, what I claim as new, and desire to secure by Letters Patent, is—

1. The arrangement of the spring bolt b, lever D E or D', and connecting rods and arms d e e' g g', in combination with the door C C' of a street-car or omnibus, constructed and operating substantially as and for the purpose shown and described.

2. The arrangement of the lip i, projecting from the inner surface of the door C, in combination with the spring-step F and registering apparatus G, constructed and operating substantially as and for the purpose herein specified.

S. R. STINARD.
